UNITED STATES PATENT OFFICE.

OWEN BURNS, OF CHICAGO, ILLINOIS, ASSIGNOR TO THE W. F. BURNS COMPANY, OF SAME PLACE.

COIN-RECEPTACLE.

SPECIFICATION forming part of Letters Patent No. 664,990, dated January 1, 1901.

Application filed October 13, 1900. Serial No. 32,934. (No model.)

To all whom it may concern:

Be it known that I, OWEN BURNS, a citizen of the United States, residing at Chicago, in the county of Cook and State of Illinois, have 5 invented a new and useful Coin-Receptacle, of which the following is a specification in its best form now known to me, reference being had to the accompanying drawings.

My invention relates to coin-receptacles, 10 and particularly to those of savings-banks. Its object is to provide a chamber in which coins can be inserted through an opening in the outer wall and from which the coin can only be withdrawn by unlocking the door.

15 My invention consists, essentially, of an antechamber within the main chamber in the receptacle, to which a coin is admitted through an opening in the outside of the box, and an opening leading from the antechamber to the main chamber, so placed that the coin has to be tilted through a substantial angle, preferably about ninety degrees, from its position when it enters the antechamber before it can pass through the second slot.

20 It also consists in means operable from the outside of the box for so tilting the coin. I have found that in a box so constructed it is impossible to extract a coin from the inner chamber through the path by which the coin entered. I do not limit myself to the exact 25 details of construction, which may be greatly varied without departing from the broad principle of my invention.

My invention also consists of the details of 30 construction hereinafter more fully described and claimed.

In the drawings, Figure 1 shows in perspective the exterior of the coin-box; Fig. 2, a sectional view showing the interior of the 35 box, with the interior mechanism in the position it assumes when the coin has just been inserted from the outside; and Fig. 3 shows the position of the parts just before the coin is allowed to pass from the antechamber into the inner chamber. Fig. 4 shows a modified 40 form of construction.

The bank consists of the box *a*, which may be of any size or shape desired. It has a door *b*, normally secured by the lock *c*, so that coins 45 cannot be removed by mischievous persons.

In the end of the box is the slot *d*, through which extends the upper end *e* of the lever or latch-plate *f*, which is pivoted at *g* to the front and rear of the box *a*. This latch may be pivoted at various points; but I find that 55 it works best when pivoted at one side of the plane of its surface, about as shown. This latch-plate *f* is substantially the width of the interior of the box. Rigidly secured to the top and sides of the box is the plate *h*, extending down so that its end *i* is about a quarter to three-eighths of an inch above the end *k* of the lever *f* when in its lowest position. Pivotedly mounted at *l* on the under side of *h* and normally forming an extension of it is 60 another latch *m*, having its lower end *n* weighted, so that when the box is in the vertical position the latch *m* will be in the position shown and about the width of the largest coin from the end *k* of the latch *f*. If the box 65 is inverted, the end *n* will fall against the end *k* and close the opening. It will be seen that the plate *h* and the latches *f* and *m* thus form an antechamber *o*, having as an entrance from the outside the slot *d* (which is so proportioned that when the end *e* of the plate *f* is depressed the largest coins, as silver dollars or twenty-dollar gold pieces, will pass through it) and as an entrance to the inner 70 chamber *p* the opening between *k* and *n*. 75

In operation the box is first locked and placed where it is to stand for the reception of money. A person desiring to deposit money in the box takes hold of lever *e* and depresses it, as shown in Fig. 3. He now inserts the 80 coin in the slot *d* and releases both it and the lever, with the result that the coin *r* settles to the position shown in full lines in Fig. 2, its lower edge lying across the opening *k* *n* and at right angles to it. The operator now again 85 presses the handle *e* and in so doing tilts the coin first to the position shown in dotted lines *r'*, Fig. 2, and finally to that of *r''*, Fig. 3, where the coin has passed the vertical and is at substantially ninety degrees from its original position. In doing this the coin has been held from slipping by resting against the end *i* of the plate *h*. In other words, this end *i* has acted as a fulcrum on which to turn the coin. The operator now releases the handle 90 95 100

e, thereby allowing the plate *f* to fall to its lowest position and the coin to pass between *k* and *n* into the interior chamber *p*.

If desired, the lever *f* may be shortened, 5 as shown in Fig. 4, and a bar *s* secured across the box and in the same plane with the lever when in its lowest position, the lower edge *t* of this bar being in the same position with reference to *n* that *k* is in Figs. 2 and 3. The only 10 variation in the operation is that the coin is tilted by a jerking instead of a steady motion of the lever *f*. In other words, the coin is flipped over by a blow from lever *f* instead of being slowly turned over in the manner 15 shown in Figs. 2 and 3 and heretofore described.

Having thus described my invention, what I desire to secure by Letters Patent is—

1. In apparatus of the class described, the 20 combination of a box having a slot in one of its outer walls, an antechamber within said box having a slot, approximately at right angles to the first slot, leading from the antechamber to the inner chamber, and a latch- 25 plate, having one end extending through the outside slot, adapted when operated from without to tilt a coin in the antechamber from its position after entering the outside slot to the position required to pass through 30 the inner slot.

2. In apparatus of the class described, the combination of the box having a slot in one of its outer walls, a latch-plate pivotally mounted within said box having its upper 35 end extending through said slot, a partition-wall forming an antechamber above the upper side of said plate, and a coin-slot substantially at right angles to the plane of said pivoted plate, leading into the inner chamber 40 of the box.

3. In apparatus of the class described, the combination of a box having a slot in one of its outer walls, a latch-plate pivotally mounted within said box having its upper end extending through said slot, a partition-wall inclosing the end of said latch so as to form an antechamber around the upper end of said latch, the end of said partition-wall being such a distance from and in the plane of the 50 end of the latch-plate that a slot is left for the passage of a coin from the antechamber into the inner chamber.

4. In apparatus of the class described the combination of the box having a slot in one of the outer walls, a latch-plate pivotally mounted within said box having its upper end extending through said slot, a partition-wall inclosing the end of said latch so as to form an antechamber around the upper side of said 55 latch, the end of said partition-wall being at such a distance from, and in the plane of, the

end of the latch-plate that a slot is left for the passage of a coin from the antechamber into the inner chamber, and a projection on said partition adapted to engage the edge of 65 a coin so that it may be turned through a large angle substantially as described.

5. In apparatus of the class described the combination of the box having a slot in one of the outer walls, a latch-plate pivotally mounted 70 within said box having its upper end extending through said slot, a partition-wall inclosing the end of said latch so as to form an antechamber around the upper side of said latch, the end of said partition-wall being at 75 such a distance from, and in the plane of, the end of the latch-plate that a slot is left for the passage of a coin from the antechamber into the inner chamber, and mechanism for automatically closing said slot when the box 80 is moved substantially from its normal position substantially as described.

6. In apparatus of the class described the combination of a box, a slot *d* in one wall, a latch or lever *f* pivotally mounted within the 85 box having its upper end *e* extending through said slot, a partition-wall *h* inclosing the upper side of latch *f* so as to form the antechamber *o*, the lower edge *i* of partition *h* being adapted to act as a fulcrum for turning a 90 coin and a second latch *m* pivotally mounted on the partition *h* with its lower edge *n* normally in the plane of, and a coin's width from, the end *k* of the latch *f*, substantially as shown and described. 95

7. In apparatus of the class described the combination of a box having a slot in one of its outer walls, an antechamber within said box having a slot, approximately at right angles to the first slot, leading from the antechamber to the inner chamber, and a lever having one end extending outside the box adapted when operated from without to tilt a coin in the antechamber from its position after entering the outside slot to the position 105 required to pass through the inner slot.

8. In apparatus of the class described the combination of a box having a slot in one of its outer walls, an antechamber within said box having a slot, approximately at right angles to the first slot, leading from the antechamber to the inner chamber and a latch-plate, adapted to normally close the outer slot, having a portion extending outside the box, adapted when operated from without to 110 tilt a coin in the antechamber from its position after entering the outside slot to the position required to pass through the inner slot. 115
